COMPARTMENT SHOWER

Howard G. Mullett, Milwaukee, Wis., assignor to
 Bradley Washfountain Company, Milwaukee,
 Wis., a corporation of Wisconsin

Application July 25, 1938, Serial No. 221,088

3 Claims. (Cl. 4—145)

The invention relates to showers and more particularly to group or compartment showers.

Heretofore, in the manufacture of group showers it has been usual to prepare a special foundation or base for the shower which had to be done on the site and generally necessitated either very heavy or special supporting construction. This had the effect of limiting the use of group showers in most instances to new buildings. The object of the present invention is to provide a shower structure which does not require a special foundation for its installation and which can be made at the factory and shipped to the place of use ready for installation. The construction also isolates the drain water of each compartment from the other.

A further object of the invention is to provide a group shower structure in which each of the shower units is separately drained so that the same is more sanitary than the usual group shower since drain water from one shower compartment cannot spread out into an adjacent compartment.

A further object of the invention is to provide a shower in which the base is formed of a plurality of units which may be readily assembled together and associated with a common drain.

The invention further consists in the several features hereinafter set forth and more particularly defined by claims at the conclusion hereof.

In the drawings:

Fig. 1 is a plan view of a shower structure embodying the invention, parts being broken away;

Fig. 2 is a section taken on the line 2—2 of Fig. 1;

Fig. 3 is an enlarged detailed sectional view taken on the line 3—3 of Fig. 2;

Fig. 4 is a detailed sectional view taken on the line 4—4 of Fig. 3;

Fig. 5 is a detailed plan view of one of the base units;

Fig. 6 is an enlarged detailed sectional view taken on the line 6—6 of Fig. 5;

Fig. 7 is a detailed sectional view taken on the line 7—7 of Fig. 1;

Fig. 8 is a detailed sectional view taken on the line 8—8 of Fig. 7;

Fig. 9 is a detailed perspective view of a waterproofing member;

Fig. 10 is a plan view of base structure for a semi-circular shower.

Referring to the drawings, the shower embodying the invention includes a plurality of base units 12 of generally sector-shaped form which may be assembled together to form either a cir-

cular or substantially semi-circular shower foundation. Each of the units 12 is dished to form a basin 13 with the converging side walls 14 and the front wall 15, the bottom of said basin tapering from said front wall toward the inner end 16 of said unit and having a roughened or non-slipping circular area or spot 12'. The inner end 16 is provided with a drainage opening which is here formed by a metal drain chute 17 which is inset in the material forming the body of the unit. As herein shown the body is formed of a terrazzo concrete which is cast to the desired form, but it may be formed of cast or pressed metal if desired, the roughened spot 12' being formed by small spaced projections extending up from the main surface of the bottom. The front side 18 of the end 16 is curved to conform to the curvature of a cylindrical drain fitting 19 which has a lower annular flange 20' and flange projections 20 between which the top and bottom sides of the front end 16 fit and openings 21 to receive the inner ends of the chutes 17.

The drain fitting 19 forms the base for a tubular post or standard 22 which is fitted into the upper portion of the same. A collar 23 covers the top of the fitting 19 and also a cement filling 23' beneath the same. The fitting 19 has a threaded opening 24 in its lower end to take the drain pipe 25 and has an annular foot portion 26 at its lower end resting on the regular base floor 27 of the building in which the structure is to be installed. The chutes 17 project inwardly to such an extent as to discharge the waste directly into the pipe 25.

The base units 12 are adapted to rest on the top or finish flooring 28 which is cut out over the foot portion 26, the inner end of the base units resting on the flange 20', there being drainage openings 30 in the fitting 19 adjacent the foot portion 26. There is also a peripheral strengthening flange 29 on the portion 26 which rests upon a recessed portion 28 of the finished flooring 28 and largely transmits the load of said fitting and standard thereto. This flange 29 is provided with holes (not shown) for the reception of screws to fasten the fitting 26 to the floor.

Short studs 31 are mounted in complementary recesses 32 in adjacent base units, as shown in Fig. 7 or in the outer sides of the units as indicated in the semi-circular base at 32' in Fig. 10. In either case these studs 31 form stops against which set screws 34 on posts 33 fitting over said studs may abut so as to initially cant the upper ends of said posts outwardly from the center of the structures so that they may be brought in-

wardly to upright positions by the radially disposed tie rods 37 which connect them with the head fitting 38 on the standard 22. At its lower end each pipe and its set screw 34 is covered over by a collar 35. The uprights 33 are connected together at their upper ends by curved frame members or bars 36. Inlet pipes 39 and 40 for hot and cold water lead to any suitable arrangement for mixing the same to provide a supply of tempered water, that shown in the present application being similar to that shown and described in detail in U. S. Patent No. 1,747,838, dated February 18, 1930, to H. A. Mullett and Herman E. Heine and including the control valves 41 and 42 for the hot and cold water respectively, the tempered water proceeding from the mixing chamber to the pipes 43, each of which has a suitable shower sprayhead 44.

Partitions 45 are mounted between the uprights 33 and the standard 22 to form the compartments, one sprayhead discharging into each compartment. The details of the partition and the method of its attachment to the framing will be found in the prior U. S. Patent No. 2,042,547, dated June 2, 1936, to H. A. Mullett. Reference is also made to U. S. Patent No. 1,821,229, dated September 1, 1931, to Howard A. Mullett and Herman E. Heine for other arrangements of mixing valve and framing that may be used with the base units previously described.

Flexible curtains 46 may be suspended on the bars 36 for movement relative thereto. Metal strips 47 may be laid over the tops of the adjoining sides 14 of the units and be secured in this position by inserting their inner ends 48 beneath the flanges 20 and bringing their outer end portions over the curved ends of the rear wall 15 down through a recess 49 formed by complementary recesses in adjoining sections and securing them by brazing to a similar metal band 50 that surrounds the units adjacent their bases. The strips 47 prevent water working into the cracks between adjacent units, and the band 50 functions principally as a finishing member and con-

ceals openings that may exist between the wooden floor and the bottom of the basins or receptors.

The above described shower construction can be supplied complete at a lower cost than where the base has to be formed at the site and permits the installation of showers in old buildings not suitable for the built-in shower.

I desire it to be understood that this invention is not to be limited to any particular form or arrangement of parts except in so far as such limitations are included in the claims.

What I claim as my invention is:

1. In a shower apparatus, the combination of a base formed of individual sector-shaped basins arranged in abutting relation, the fronts of said basins being recessed at their adjoining edges, metal covering strips extending over the abutting sides of said basins and through said recesses at the fronts of said basins, a metal band surrounding the assembled basins, the lower ends of said strips at the fronts of said basins being secured to said band, and a common drain into which said basins discharge.

2. In a shower apparatus, the combination of a base formed of individual sector-shaped basins arranged in abutting relation, a common drain into which said basins discharge, the abutting sides of said basins having complementary recesses, rods mounted in said recesses, compartment framing for said basins including uprights, and a wedging connection between said uprights and said rods.

3. In a shower apparatus, the combination of a drain fitting having a tubular standard receiving portion and spaced upper and lower flanges at its lower end portion, individual sector-shaped basins arranged in abutting relation and supported at their inner ends on the upper of said flanges, the inner ends of said basins each having a discharge portion communicating with said fitting, the lower of said flanges providing a supporting base portion, and a drain pipe connected to the base of said drain fitting.

HOWARD G. MULLETT.
